mesne assignments, to Varian Associates, a corpora-
tion of California

Filed Dec. 31, 1962, Ser. No. 248,499

8 Claims. (Cl. 332—7)

This invention relates to a phase shift neutralizer and more particularly to apparatus for neutralizing phase shift due to velocity variation in the beam of a beam type tube such as a klystron.

In beam type tubes, there is a space charge variation in the beam itself due to the negative charge on the individual electrons within the beam. As the beam passes through accelerating electrodes, the accelerating voltage affects those electrons at the outer surface of the beam to a greater extent than the electrons at the center of the beam. As the beam becomes more dense, the degree of penetration to the interior is reduced. Consequently, there results a velocity variation across the beam which is dependent upon the beam density. As the beam becomes denser, the average velocity of the beam for the same accelerating voltage is reduced. In a typical application, the change in average beam velocity can be as much as 5%.

In a modulating anode type beam tube, there is generally provided a source of electrons, a modulating anode which controls the beam density, an accelerating anode which controls the velocity of the beam, and a radio frequency section which interacts with the beam to form the output signal. Similarly, in tubes which employ a grid structure for controlling the beam density, there is provided an accelerating anode. It is readily apparent that when the intensity of the beam is varied to derive a desired variation in beam intensity as, for example, in the derivation of shaped output pulses such as Gaussian pulses or amplitude modulated output signal, the side effect is to also provide a variation in beam velocity. The variation in beam velocity affects the phase of the output of the radio frequency section associated with the beam. Between the minimum current density and the maximum current density, there may be a considerable phase shift which, of course, distorts the output pulse or signal.

It is, therefore, a general object of this invention to provide apparatus and method for neutralizing the phase shift due to velocity variation in the beam of a beam type tube.

It is another object of this invention to provide an apparatus and method for neutralizing phase shift due to velocity variation of a modulated beam type beam tube such as a klystron including a modulating anode or other modulating electrode.

It is a more particular object of this invention to provide an apparatus and method to neutralize velocity variation type phase shift in beam type tubes by providing an external feedback circuit which is responsive to the beam current.

These and other objects and features of the invention will become more clearly apparent upon a review of the following description in conjunction with the accompanying drawings.

Referring to the drawing:

FIGURE 1 is a schematic diagram of a beam projection and interception means with one feedback circuit; and

FIGURE 2 is a schematic diagram of a beam projection and interception means with another feedback circuit.

Referring to FIGURE 1, there is shown an electron gun 11 for a beam type tube. The gun includes a cathode 13 heated by a filament 15 and situated within a focusing

electrode 17. The cathode 13 and focusing electrode 17 are connected to the cathode terminal 19. Disposed in front of the cathode 13 is a modulating anode 21 and an accelerating anode 23. Radio frequency structures may be disposed to interact with the beam, for example, in a klystron. Various resonators and cavities are disposed along the beam. A radio frequency structure is not shown in the drawing since it is not deemed to importance to the instant invention. However, a collector 25 is shown at the opposite end of the klystron unit in axial alignment with the cathode 13 and the anodes 21 and 23. The collector interrupts and collects the beam.

An inductor 27 is connected to the cathode terminal 19 and the opposite end of the inductor is coupled through the parallel connected capacitor 29 and power supply 31 to the accelerating anode 23. Also connected between the inductor 27 and the anode 23 is a pair of series switching tubes 33 and 35. The junction of the anode of tube 33 and cathode of tube 35 is connected to the modulating anode 21. Modulating voltages may be applied to the grids of the tubes 33 and 35 in conventional manner to modulate the beam current.

A capacitor 37 and a resistor 39 are serially connected between the cathode terminal 19 and the anode 23. The junction of the capacitor 37 and the resistor 39 is connected to a source of positive voltage B+ through vacuum tube 41. The grid is controlled by a voltage applied through transformer 43, the secondary of which is connected between the grid and cathode of tube 41. The primary of the transformer is connected between the positive terminal of the power supply 31 and the collector 25. It will be apparent to one skilled in the art that a solid state device may be substituted for the tube 41.

In normal operation of the beam-type device similar to that shown (but ignoring the inductor 27, capacitor 37, resistor 39, tube 41 and transformer 43), the electron beam 45, as it passes through the anodes 21 and 23, includes a substantial negative charge to the electrons within the beam itself. As modulating voltage is applied by the modulating anode 21 to vary the beam current, the beam acceleration due to the fields from the accelerating anode changes. As the beam becomes denser, the electrons near the outer perimeter of the beam 45 are affected by the accelerating voltages to a greater degree than those electrons near the center of the beam which are relatively isolated from the accelerating voltage. Thus, the outer portion of the beam is accelerated to a greater extent than the inner portion. The velocity of the electrons varies from the inner to the outer portion of the beam. As the beam intensity is varied under the influence of the modulating anode, the degree of penetration, thus acceleration changes and there is a change in the average velocity of the beam, as previously described.

Since phase shift in the output of the radio frequency section is caused by the change in beam velocity, the phase shift is proportional to the beam density. The beam density may be easily detected at the collector 25 and, in accordance with this invention, is used as a feedback signal to neutralize the phase shift. The beam density is controlled by controlling the degree of conduction of each of the tubes 33 and 35.

In accordance with the invention, a feedback signal is derived which serves to increase the accelerating voltage as the beam density increases whereby to maintain substantially constant beam velocity with changing beam current. The feedback circuit, previously described, includes the collector 25 connected to the primary of a transformer 43 whereby the beam current passes through the primary and induces a voltage between the grid and cathode of the tube 41 which is proportional to the current to thereby control the conduction of the tube 41. The current for the tube is supplied through the inductor 27. The voltage

drop across the inductor 27 changes and adds to or subtracts from the accelerating voltage. The transformer 43 is phased so that the tube 41 conducts less current as the beam current increases to thereby reduce the voltage drop in the inductor and increase the accelerating voltage.

Another circuit for performing the same function as those shown in FIGURE 1 is shown in FIGURE 2. Like parts bear like reference numerals. Thus, the inductor 27, capacitor 29, power supply 31, tubes 33 and 35 bear like reference numerals to perform the same functions. The means for deriving the feedback signal again comprises a transformer. The transformer 51 which has its primary serially connected between the positive terminal of the power supply and the positive terminal of an auxiliary power supply or battery 52 which, in turn, has its negative terminal connected to the collector thereby provide a depressed collector connection. The secondary of the transformer has one terminal connected to the positive terminal of the power supply and its other terminal connected to the cathode lead through a capacitor 54. There is provided a voltage limiting diode 53 between the positive terminal of the power supply and the common terminal of the capacitor 54 and secondary of the transformer 51.

Operation of the circuit is to circulate a current dependent on beam current in the loop including the power supply 31, secondary of transformer 51, capacitor 54 and inductor 27. The circulating current increases and decreases as the beam current increases and decreases and, in turn, the accelerating voltage is controlled to maintain a constant average beam velocity.

Thus, there is provided a means responsive to beam current for neutralizing velocity variations in a beam resulting from the modulation of the beam density.

I claim:

1. A circuit for eliminating phase shift due to velocity variation arising from variations in beam density in a beam tube having an accelerating means, a cathode and a collector, means for applying an accelerating voltage to said accelerating means, and feedback means responsive to the intensity of said beam connected between said collector and said accelerating means for varying said accelerating voltage in direct proportion to the said variations in beam density.

2. In an electron beam type tube of the type which includes a cathode, an accelerating anode for accelerating electrons leaving the cathode, a beam current modulating electrode for modulating the beam current, and a collector for intercepting the beam, means for applying an accelerating voltage between the cathode and anode, means for applying a modulating voltage between said cathode and said modulating electrode, and means responsive to the collector current for varying the accelerating voltage between the cathode and anode in direct proportion to the beam current to neutralize velocity variations in the beam due to variations in beam current.

3. A circuit for minimizing phase shift due to velocity variation arising from variations in beam density in a beam tube including a cathode and a collector between which an electron beam is projected, accelerating means for controlling the beam velocity, means for applying an accelerating voltage to said accelerating means, and feed-

back means responsive to the density of said beam connected between said collector and said accelerating means for varying the accelerating voltage applied to said accelerating means in direct proportion to said variations in beam density.

4. In an electron beam type tube of the type which includes a cathode, an accelerating anode for accelerating electrons leaving the cathode, a beam current modulating means for modulating the beam current, and a collector for intercepting the beam, means for applying an accelerating voltage between the cathode and anode, and means responsive to the collector current for varying the accelerating voltage between the cathode and anode in direct proportion to said beam current to neutralize velocity variations in the beam due to variations in beam current density.

5. A circuit for minimizing phase shift due to velocity variations arising from beam density variations in a beam tube including a cathode and a collector between which an electron beam is projected, accelerating means for controlling the beam velocity, means for applying an accelerating voltage to the accelerating means, and feedback means including the primary windings of a transformer connected in the collector current path, and means associated with the secondary windings of said transformer for varying the voltage applied to said accelerating anode.

6. A circuit as in claim 5 wherein said means associated with the secondary winding of the transformer comprises an inductor connected in series with said means for applying an accelerating voltage to said accelerating means, and means for causing current to flow in said inductor in response to changes in beam current.

7. An electron beam type tube including a cathode, an accelerating anode for accelerating electrons leaving the cathode, a modulating anode disposed in the electron path between the cathode and accelerating anode, means for controlling the voltage on the modulating anode to modulate the beam current, a collector spaced from the accelerating anode and serving to collect the electrons, means for applying an accelerating voltage between the cathode and accelerating anode, and means responsive to the collector current for varying the accelerating voltage in direct proportion to said beam current to neutralize velocity variations in the beam due to variations in beam density.

8. An electron beam type tube as in claim 7 wherein said last named means includes a transformer having primary and secondary windings, said primary windings being connected in the collector current path and said secondary winding being connected in circuit with means for varying the accelerating voltage responsive to beam current density.
